UNITED STATES PATENT OFFICE.

THOMAS J. HAYES, OF EAST ST. LOUIS, ILLINOIS, ASSIGNOR TO LEWIS FELLING MACHINE COMPANY, OF ST. LOUIS, MISSOURI, A CORPORATION OF DELAWARE.

SEWING-MACHINE FEED MECHANISM.

Application filed May 31, 1921. Serial No. 474,081.

To all whom it may concern:

Be it known that I, THOMAS J. HAYES, a citizen of the United States, residing at East St. Louis, in the county of St. Clair and State of Illinois, have invented certain new and useful Improvements in Sewing-Machine Feed Mechanism, of which the following is a specification.

It is a long-recognized fact that in the operation of standard high speed sewing machines of the straight-needle type for through and through stitching—machines such as the Singer sewing machine commonly used in tailoring establishments—the lower ply or layer of goods, being directly engaged by the four way feed-dog, tends to feed faster than the superimposed ply or layer that engages the relatively stationary presser-foot; and it is also known that under many conditions the utmost skill of the operator in effort to compensate for this tendency of the one layer to creep with respect to the other layer are ineffectual. Generically, the matter of providing an upper feed-dog to work in conjunction with a usual, lower feed-dog is well known, very many machines having been devised or marketed containing one form or another of overhead feed mechanism, but I believe it to be true that no overhead feed mechanism has been produced prior to my present invention that is contained in and supported wholly by the presser-foot and is capable of operation in these high speed machines without in any way interfering with speed-capacity or the facility with which they can be operated in any particular; nor, I believe, has such an overhead feed mechanism been heretofore provided that would be applicable to standard-type sewing machines by mere substitution of a feed-carrying presser-foot for the ordinary presser-foot and a different needle-bar clamp for the ordinary needle-bar clamp. The general objects of my invention are to provide an overhead feed mechanism for the class of machines above stated and characterized by the features above noted; and more specific objects of my invention are to provide combinations of parts for the provision of an overhead feed that will be simple, effective, durable, adapted for high speed operation and effectively adjustable for the most precise cooperation with the normal or lower feed-dog. To these ends my invention consists in the combinations and ar-

rangements of parts hereinafter more fully described and claimed, reference being had to the accompanying drawings wherein I have shown for illustrative purposes a single embodiment of my invention in a form 60 which I have found to be efficacious and desirable.

In the drawings Fig. 1 is a side elevation of an upper feed attachment related to appropriate parts of a Singer sewing machine; 65 Fig. 2 is an elevation from the opposite direction; Fig. 3 is a section on line 3—3 of Fig. 5 with the parts in a position different from that shown in Figs. 1 and 2; Fig. 4 is a detail section on line 4—4 of Fig. 2; Fig. 70 5 is a front elevation of the attachment; that is to say as seen from the right of Fig. 1; Fig. 6 is a plan view of the attachment with the presser-foot bar in section; Fig. 7 is an inverted plan view of the attachment; Fig. 8 75 is a perspective detail of the lower portion of the presser foot frame, and Fig. 9 is a perspective detail of the upper feed dog.

In the drawings head 10, needle-bar 11, needle 12, presser-foot bar 13, work-plate 14 80 and lower feed-dog 15, the latter being variable as to fore-and-aft throw, of its four-way motion, all represent standard sewing machine parts as of a Singer machine. For the ordinary needle-clamp is substituted one 85 as shown at 16 having provision such as stud 17 to cooperate with the forked end 18 of an actuator lever 19 for the upper feed mechanism. The entire upper feed mechanism is carried in a presser foot frame, that is to say, 90 in a frame providing a presser foot part and substitutable on the presser-foot bar 13 for the ordinary presser foot of the machine, this presser-foot frame as a whole being indicated at 20, and the presser-foot proper 95 indicated at 21. Through the presser-foot works the upper feed-dog 22 to which four-way feeding motion is to be imparted in accordance with the vibrations of the needle-bar-operated actuator 19. Specifically the 100 dog, normally pressed upwardly and forwardly by spring 23, vibrates fore-and-aft with the feed lever 24 and rises and falls under control of the depressor lever 25, both of which are mounted in the presser-foot frame 20 and both of which may be actuated by a cam structure 26 that is operatively connected with the actuator bar 19. As the needle bar rises the actuator, turning the cam structure 26, causes first the depressor lever 105 110

to force down the upper feed-dog against the tension of its spring 23, and then causes the feed lever 24 to advance (rearwardly across the machine or in the direction of the feed)

5 the depressed feed-dog against the tension of spring 23; down-stroke of the needle reversing the travel of the cam and permitting spring elevation and spring retraction of the upper feed-dog to complete the four-way 10 cycle.

Now specifically to describe the preferred construction illustrated in the drawings, frame 20 is preferably made in two major parts, the head 28 and foot 29 secured together by screws 30, the base portion or foot 15 proper 21 having made therein slots 31 to receive the toothed portions 32 of the feed-dog 22 that are separated to work in conjunction with the corresponding feed points 20 of the main dog 15 on opposite sides of the needle, there being a wear plate 33 preferably mounted upon and between the side portions of the feed-dog to receive the thrust of the depressor lever 25. The head portion 25 28 of the attachment, socketed as at 34 to receive the extremity 35 of the presser foot bar and be retained by screw 36, extends upwardly and rearwardly and near its upper end has mounted in the boss 37 a headed 30 bearing stud 38 on which are mounted the actuator lever 19, and the controlling cam 26, in arrangement best shown in Figs. 2 and 4. The cam 26 has spacing hub projections 40 and 41, the latter affording a 35 bearing for the pivoted end of lever 19, adjustment between the lever and cam being provided by the arcuate slot 42 in the lever and the wing-screw 43 extending therethrough and tapped into the side of the 40 cam. Of course the actuator 19 has a fixed range of motion, and the adjustment aforesaid between it and the cam is intended to vary the throw of the feed-dog fore-and-aft from zero to maximum length. The 45 feed cam surface 45 works against the upper portion of the feed lever 24 that is pivoted on a stud 46 projecting from the frame, the lower end of said lever having pivotal connection 47 with the solid rear 50 end of the dog 22. Of course when the wing-screw 43 is adjusted clear to the rear end of its slot 42, cam nose 45 is not brought into effective contact with the lever 24 which remains in contact with the concentric surface 45' of the cam as a back-stop.

55 The depressor lever 25 may best be worked in invariable time-relation to the operation of cam 45, and should be ineffective to depress the feed-dog when the cam 45 is thrown to inactive position. To these ends the cam member 26 carries a laterally extending roller-bearing stud 50 that cooperates with the cam-shaped upper extremity 51 of the depressor lever 25, said lever 60 being pivoted on the stud 46 and having a

clearance slot 52 encompassing the hub portions 40 of the cam 26. As the roller of stud 50 rides up the appropriate cam-surface, from depression 53 to the position shown in Fig. 3, it rocks the upper end of 70 the depressor lever forwardly to a definite extent, causing the forwardly extending nose of the bell crank depressor lever to press down the upper feed dog and then, as the roller idles along the suitably curved 75 surface 54, it holds the depressor lever down. When the cam structure 26 is adjusted to inactive position (with the wing screw 43 at the extreme rear end of its slot, Fig. 2) 80 the roller of stud 50 never acts upon the cam to depress the lever 25. The positiveness of action and range of adjustment of the feeding mechanism of the attachment enables it to be used, on occasion, to work against a solid plate, rather than in conjunction with 85 a main feed dog 15.

Spring 23 may take divers forms suitable to both lift and press forward the feed-dog 22, such spring in the construction shown 90 having an end 56 anchored between the boss 37 and the spring stud 57 and having nearly a right-angle course downward and forward therefrom, preferably with a coil 58 in the angle, to the hook portion 59 that engages a 95 pin 60 on the feed-dog.

It will be understood by those skilled in the art that changes in details of construction may be made without departure from the spirit and scope of my invention and that some specific variations may be necessitated by differences in construction of particular sewing machines to which the invention may be applied.

I claim:

1. As an article of manufacture, a sewing 105 machine attachment comprising a frame having a presser foot portion and substitutable for a standard presser foot, a four-way movable feed-dog mounted in the presser foot portion, means for imparting four-way motion to said feed-dog wholly carried by said frame, said means including an actuator constructed and arranged for connection with a needle bar to be vibrated therefrom.

110 2. The combination with a sewing machine having a normal presser foot bar, needle bar and four-way lower feed-dog, of a presser foot structure carried by said presser bar and comprising a frame, an upper feed dog mounted in said frame, cam controlled means for imparting four-way motion to said upper feed-dog, and actuating means for said cam comprising an actuator lever connected to the needle bar for vibration therewith.

115 3. A presser foot feed attachment, for a sewing machine that comprises a vertical presser bar, a vertical needle bar in front thereof, and a main four-way feed, comprising a frame detachably connectible with 120

- the presser bar, said frame providing a presser foot portion slotted to receive a feed-dog, an upper feed-dog working through said presser foot portion, and means for imparting four-way feeding movement to said dog, wholly carried by said frame and including an actuator lever operatively connectible with the needle bar. 5
4. A sewing machine attachment of the character described, comprising a presser foot frame, a feed-dog arranged for four-way motion therein, means including a feed-lever for imparting fore-and-aft motion to said dog; means including a depressor lever for imparting vertical motion to said dog, a cam device controlling said levers jointly, and an actuating lever operatively connectible with said cam device. 10
5. A sewing machine attachment of the character described, comprising a presser foot frame, a feed-dog arranged for four-way motion therein, means including a feed-lever for imparting fore-and-aft motion to said dog; means including a depressor lever for imparting vertical motion to said dog, a cam device controlling said levers jointly, and an actuating lever adjustably connectible with said cam device. 15
6. A sewing machine attachment of the character described comprising a presser frame having a slotted foot portion, an extension in rear of and above said foot portion, a bearing stud in said extension, a cam structure bearing on said stud, an actuator lever operatively connected with said cam structure, a feed-dog arranged to work in the foot-slots, spring means normally tending to elevate said dog and throw it forwardly, and lever means controlled by said cam for depressing said feed-dog and imparting movement thereto in the direction of the feed. 20
7. The combination with a sewing machine having a vertically reciprocable needle bar, a vertical presser bar in rear thereof, a work plate and a lower feed dog operating through the work plate, of a presser foot having a slotted foot-proper and having a frame extension above and in rear of its point of connection with the presser bar, an actuator mounted in said extension and connected with the needle bar to be oscillated vertically by reciprocation of the needle bar, a feed-dog working through the presser foot slots and arranged to receive four-way motion, and means responsive to movements of said actuator and carried by said presser foot frame for imparting four-way movement to said feed-dog. 25
8. An attachment for a sewing machine of the character described, comprising a frame having a presser foot slotted to receive a feed-dog, a feed-dog arranged to work therethrough, an actuator pivotally carried by said frame and adapted for operative connection with a needle bar, a cam-structure adjustably connected with said actuator, a feed lever and a depressor lever pivoted in said frame, operatively associated with said feed-dog and arranged to be vibrated by movement of said cam-structure to impart feeding and depressing motion to the feed-dog, and a spring mounted in said frame for restoring said feed-dog to raised retracted position. 30
9. A sewing machine attachment of the character described, comprising a presser foot frame, a feed-dog arranged for four-way motion therein, cam-controlled means on said frame for imparting four-way motion to said feed-dog, and actuating means for said cam constructed and arranged for connection with a needle bar to be vibrated therefrom. 35
10. A sewing machine attachment of the character described, comprising a presser-foot frame, a feed-dog arranged for four-way motion therein, a spring tending to raise and retract said dog, a lever for advancing said dog, a lever for depressing said dog, a cam device controlling said levers jointly, and an actuating lever connected with said cam device. 40
11. A sewing machine attachment of the character described, comprising a presser-foot frame and, mounted on said frame, the combination of a feed-dog arranged for four-way motion, a pivoted feed lever for imparting four-and-aft motion to said dog, a pivoted depressor lever for imparting vertical motion to said dog, cam means for actuating said levers, actuating means constructed and arranged for connection with a needle bar to be vibrated therefrom, and adjustably connected with said cam structure to actuate the latter, and spring means constantly tending to move said feed-dog to raised, retracted position. 45
12. As an article of manufacture, a sewing machine attachment comprising a frame having a presser-foot portion and substitutable for a standard presser-foot, a four-way movable feed-dog mounted in said presser-foot portion, means for imparting four-way motion to said feed-dog wholly carried by said frame, and adjustable to vary the feeding-length of the movement of said dog, said means including an actuator constructed and arranged for connection with a needle bar to be vibrated therefrom. 50
13. The combination with a sewing machine having a normal presser-foot bar and needle bar, of a presser-foot structure carried by said presser-foot bar and comprising a frame, a four-way feed-dog mounted in said frame, cam controlled means for imparting four-way motion to said feed-dog, and actuating means for said cam comprising an actuator lever adjustably connected with said cam-controlled means to vary the 55

length of feeding movement of said feed-dog and connected to the needle bar for vibration therewith.

14. A sewing machine attachment of the character described comprising a presser-foot frame, a feed-dog arranged for four-way motion therein; means including an actuator adapted to be connected to a needle-bar for positively depressing and advancing the feed-dog and a single wire spring coact-

ing with the feed-dog and having its butt supported from the presser-foot frame, a middle coil, a generally vertical portion between the butt and the middle coil, and a generally horizontal portion extending from the middle coil and connected to the feed-dog, whereby said spring tends both to raise and retract said feed-dog.

THOMAS J. HAYES.
